UNITED STATES PATENT OFFICE.

WALTER E. WIESENTHAL, OF WICHITA, KANSAS.

OIL AND GAS BURNER.

Application filed October 4, 1923, Serial No. 666,558. Renewed June 12, 1926.

This invention aims to provide novel means whereby the supply of fuel to a burner may be regulated responsive to the pressure in a boiler which is heated by the burner, novel means being provided for securing a proper mixture of fuel and air.

It is within the province of the disclosure to improve generally and to enhance the utility of devices of the type to which the invention appertains.

With the above and other objects in view, which will appear as the description proceeds the invention resides in the combination and arrangement of parts and in the details of construction hereinafter described and claimed, it being understood that, within the scope of what is claimed, changes in the precise embodiment of the invention shown, can be made, without departing from the spirit of the invention.

In the accompanying drawings:—

Figure 1 shows in side elevation, a device constructed in accordance with the invention; Figure 2 is a longitudinal section wherein parts are shown in elevation; Figure 3 is a top plan; Figure 4 is a section on the line 4—4 of Figure 2; and Figure 5 is a transverse section.

In carrying out the invention, there is provided a casing 1 having a lateral extension 2. A mixing chamber 3 is formed in the casing 1 and has a lateral outlet 4 located in the extension 2. A fuel inlet 5 is fashioned in the casing 1 and communicates with the mixing chamber 3, there being a seat 6 at the point of communication between the fuel inlet 5 and the mixing chamber 3. A fuel pipe 7 discharges into the inlet 5. In the upper surface of the casing 1 there is an air inlet 8 which communicates with the mixing chamber 3. Air enters the inlet 8 under the control of a valve 9, which may be a pet cock connected with the casing 1 through the instrumentality of a thimble 10.

A main pressure chamber 11 is formed in the casing 1, steam or other fluid under pressure being supplied to the chamber 11 through a pressure pipe 12 mounted in one end of the casing 1 and communicating with the chamber 11. A pressure discharge nozzle 14 extends through the outlet 4 of the mixing chamber 3 and is mounted at its inner end in the casing 1, the nozzle being in communication with the main pressure chamber 11. In the outer end of the nozzle 14 there is an orifice 15. The pressure dis-

charge nozzle 14 is located in a fuel discharge nozzle 16 connected by a coupling 17 and a pipe 18 with the outlet 4 of the mixing chamber 3, the pipe 18 being mounted at its inner end in the extension 2 of the casing 1, as clearly shown in Figure 4. In order that the discharge nozzle 14 may be cleaned out readily, a plug 19 is threaded into the casing 1 in alinement with the nozzle 14.

The numeral 20 designates an auxiliary pressure chamber supported on the casing 1 by a bracket 21, a short pipe 22 establishing communication between the main pressure chamber 11 and the auxiliary pressure chamber 20. On the auxiliary pressure chamber 20, a yieldable diaphragm 23 is mounted. The diaphragm 23 is held in place by a retainer 24, in the form of a ring, connected to the pressure chamber 20 by securing elements 25, certain of which engage the upper end of the bracket 21. The retainer 24 has fulcrum ears 26 carrying a pivot member 27 whereon a lever 28 is mounted, intermediate its ends, for limited swinging movement, one end of the lever 28 being received slidably in a guide 29 on the retainer 24. A foot 30 rests on the yieldable diaphragm 23 and has an upstanding part 31, whereunto the lever 28 is pivoted as shown at 32.

A standard 33 is erected on the casing 1, the lever 28 having an opening 34 of such size that the lever may have the necessary swinging movement, the standard extending through the opening. On the standard 33, a first adjusting device 35 and a second adjusting device 36 are mounted, the adjusting devices preferably being in the form of nuts, the adjusting device 35 bearing upon the intermediate portion of the lever 28. A compression spring 37 surrounds the standard 33, one end of the spring bearing on the adjusting device 36, and the other end of the spring bearing on the lever 28.

A valve 38 controls the seat 6 and includes a stem 40 slideable in a gland 39 carried by the casing 1. A cross pin 41 is mounted in the stem 40.

The upper end of stem 40 is mounted in a bifurcated head 42 receiving one end of the lever 28, a bolt 43 or the like being carried by the head 42, and being received in an elongated slot 44 which is formed in the end of the lever 28. The pin 41 is used for two purposes. First, by way of the pin 41, the stem 40 may be rotated and adjusted in the

head 42, and, second, the nut 75 of the gland 39 may be moved upwardly until it engages the pin 41 to hold the valve 38 in open position, in case it is desired to blow out the oil line with steam.

In practical operation, the fuel is delivered through the mixing chamber 3 into the outlet 4 and from thence into the nozzle 16 by way of the pipe 18 and the coupling 10 17. Steam under pressure is delivered through the pipe 12 into the main pressure chamber 11, and moving through the nozzle 14, is discharged into the nozzle 16, a suction being created in the nozzle 16 and in the 15 chamber 3, air being drawn into the chamber 3 through the inlet 8, under the control of the valve 9, the result being that at the outlet end of the nozzle 16, there is a mixture of air, fuel and steam, the mixture burning 20 at the outlet end of the nozzle 16.

As the pressure builds up in the main pressure chamber 11, the pressure is communicated to the auxiliary pressure chamber 20 through the pipe 22, and the diaphragm 25 23 yields, swinging movement being imparted to the lever 28 by the foot 20 which rests upon the diaphragm. The left hand end of the lever 28 (Figure 2) swings downwardly, carrying with it the valve 38, the 30 space between the valve 38 and the seat 6 being lessened and the amount of fuel discharged into the chamber 3 being cut down accordingly. The pressure exerted by the 35 spring 37 on the lever 28 may be adjusted through the instrumentality of the lower nut

36, and thus, the valve 38 may be caused to close at any desired boiler pressure. The position of the lever 28, and, consequently, the position of the valve 38 with respect to the seat 6, may be regulated by adjusting 40 the position of the nut 35.

Having thus described the invention, what I claim as new, and desire to protect by Letters Patent is:—

In a device of the class described, a casing 45 having a mixing chamber and a main pressure chamber, an auxiliary pressure chamber supported by the casing and communicating with the main pressure chamber, a diaphragm responsive to pressure in the auxiliary chamber and carried by said chamber, a lever, means for fulcruming the lever intermediate its ends, means carried by the lever for rendering the same responsive to the diaphragm, a valve controlling the passage of fuel into the mixing chamber, means for connecting the valve with the lever, the two last-specified means being disposed on opposite sides of the fulcrum of the lever, a standard on the casing, adjusting devices 60 movable on the standard longitudinally thereof, a compression spring on the standard and cooperating with one adjusting device and with one side of the lever, the other adjusting device coacting with the opposite 65 side of the lever.

In testimony that I claim the foregoing as my own, I have hereto affixed my signature.

WALTER E. WIESENTHAL.
